UNITED STATES PATENT OFFICE.

JOSEPH RENÉ AYOTTE, OF CHICAGO, ILLINOIS, ASSIGNOR TO ALEXANDER AIRLESS
AUTO WHEEL CO., OF CHICAGO, ILLINOIS, A CORPORATION OF SOUTH DAKOTA.

RESILIENT WHEEL.

1,080,621.

Specification of Letters Patent.

Patented Dec. 9, 1913.

Application filed March 18, 1912. Serial No. 684,368.

To all whom it may concern:

Be it known that I, JOSEPH RENÉ AYOTTE, a citizen of the United States, and resident of Chicago, in the county of Cook and State 5 of Illinois, have invented certain new and useful Improvements in Resilient Wheels; and I do hereby declare that the following 10 description of my said invention, taken in connection with the accompanying sheets of drawings, forms a full, clear, and exact specification, which will enable others skilled in the art to which my said invention appertains to make and use the same.

This invention has general reference to 15 resilient wheels; and it consists, essentially, in the novel and peculiar combination of parts and details of construction, as herein-after first fully set forth and described, and then pointed out in the claims.

20 In the drawings already referred to, which serve to illustrate this invention more fully, Figure 1 is an elevation of a vehicle wheel constructed in accordance with my invention. Fig. 2 is a longitudinal sectional view 25 of one of the spokes of this wheel taken on line 2—2 of Fig. 1. Fig. 3 is an elevation, partly in section, of the hub and several spokes, one of the side plates of the hub being removed. Fig. 4 is a sectional elevation 30 of the major portion of the wheel, on line 4—4 of Fig. 3, the figure being drawn on an increased scale. Fig. 5 is an end view 35 of one of the spokes as seen from the rim-end thereof. Fig. 6 is a sectional view of 40 said spoke, on line 6—6 of Fig. 2. Fig. 7 is a like view on line 7—7 of Fig. 8. Fig. 8 is an elevation of a resilient wheel in which 45 the spokes are of slightly modified construction, one of the hub plates being removed to disclose the interior construction of the hub, 50 two of said spokes being shown partly in section. Fig. 9 is a detail view of one end 55 of the piston rod, illustrating a modified construction of the antifriction rollers connected thereto. Fig. 10 is a plan of the 60 same. Fig. 11 is a detail view of said piston rod end, showing a further modification of 65 said antifriction roller construction. Fig. 12 is a side elevation of Fig. 11.

60 Like parts are designated by the same characters and symbols of reference in all the figures.

The object of this invention is the production of an efficient, serviceable, and very 65 practical resilient vehicle wheel, which is

especially well adapted for use in automobiles and other vehicles.

A, in the drawings designates the rim of this wheel. It is, preferably, made of wood in sections properly jointed; and it is so 60 constructed that either pneumatic or solid tires may be employed thereon.

B designates the spokes of this wheel, there being a suitable number of these spokes employed which number depends 65 upon the diameter of the rim, and the class of vehicles on which the wheel is to be used.

C indicates the hub of this wheel, the bore 12, of which will be so constructed as to accommodate the spindle of the axle with, or 70 without, antifriction bearings. This hub comprises a side plate 13, having an inwardly extending boss 14, reduced in diameter at its end 15, and externally screw-threaded on this reduced portion to receive 75 an oil cap D, of usual design. Spaced from this side plate 13, and centered upon the reduced portion 15, there is a further end plate 16, which is removably held to the hub by said oil cap D and bolts 17, as will hereinafter more fully appear. Medially between the side plates 13 and 16 the boss 14 has a circumferential groove 18, in which there is located a roller bearing 19, preferably comprising two split-rings 20, having 80 85 spaced perforations to receive the journals of the anti-friction rollers 21.

The spokes B are of tubular construction, the bore 22 of which is cylindrical, said bore being internally screw-threaded at the end 90 nearest to the hub. At the end nearest to the rim, each spoke has a shoulder 23, and an externally screw-threaded shank 24, there being in the rim A shouldered holes to receive the shouldered portion and the shank 95 of said spokes, recesses 25, being formed in the rim to receive nuts 26, by which the spokes are secured to the rim. In the bore of each spoke there is a piston 27, snugly fitting said bore, and a piston rod 28, which, in the preferred embodiment of my invention, as illustrated in Figs. 3 and 4, bears at 100 its end on the antifriction roller 21 already mentioned. There is in this bore of the spoke a spiral spring 29, which bears at one 105 end upon the piston 27, and at its other end on an abutment, comprising a washer 30, an elastic packing 32, and a further washer 31, whereby a slightly yielding support for the spring is afforded to prevent rattling, 110

and for other obvious purposes. Each of these washers is a ring having preferably a central passage therethrough; and through the shouldered portion 23 and the shank 24

5 there is a passage 33, the end of which is constructed to receive a screw-plug 34, serving as a means for introducing a liquid to the interior of the spoke.

The piston comprises preferably two

10 disks 35, 36, in spaced relation, between which is located a packing disk 37, a further packing ring 38, being located upon the piston rod 28 adjacent to the disk 35, to serve as an auxiliary packing, in an obvious man-

15 ner. In order to properly guide the piston rod 28 in the cylindrical bore of the spoke there is placed in the open, screw-threaded end of the spoke, a gland 39, and a head 40, as clearly shown in detail in Fig. 2, packing

20 41, being placed between the head and the gland to close the end of the cylinder in the manner of a stuffing box; and, to prevent rapid wear of the bore of these two members 39 and 40, said bores are lined with har-

25 dened steel bushings 42, 43.

As shown in Figs. 3, 4, and 8, the ends of the spokes B enter the space of the hub between the side plates 13 and 16; and in order to prevent dirt or other gritty matter from 30 entering this space, there are formed at the inner margins of these plates flanges 44, 45, and in these flanges there are pockets 46, in which there are located packing rings 50, surrounding the inner ends of the spokes, whereby the object in view is attained in an 35 efficient manner. Near two adjacent ends of the spokes within the hub, there are located antifriction rollers 47, journaled upon the bolts 17 already mentioned, said antifriction 40 rollers permitting of a slight lateral movement of the spoke ends in the hub, it being desirable not to make the connection between the spokes and the hub too rigid.

It will now be observed that the weight 45 of the load carried by the wheel is transferred to the hub of the same, which will cause the hub to move vertically up and down. This load is borne upon the springs of the lower half of the spokes, or in other 50 words by those spokes that are below the horizontal center line of the wheel, which springs are thereby compressed and thus impart the resiliency to the wheel. And in order to assist these springs in the carrying 55 of said load, and at the same time to lubricate the sliding parts in the bore of the spoke, I introduce to this bore a preferably liquid lubricant, such as mineral oil, and fill the same approximately two-thirds full.

60 Thus, when the space between the piston and the abutment is contracted by the movement of the spoke, the air in the remaining space of the cylindrical bore of the spoke is compressed, which adds to the resistance 65 offered to the movement of the spoke by said

spring, and this resistance can be increased or diminished by a proper regulation of the amount of liquid poured into the spoke.

The external contour or shape of the spokes is a matter of choice. In Figs. 1 to 6 70 inclusive, I have shown spokes that are externally square in cross section and provided with longitudinally disposed strengthening ribs 48; and in Figs. 7 and 8, I have illustrated spokes which are circular in transverse section. Any other external contour of these spokes may, however, be selected as long as the spokes are provided with the cylindrical bore to receive the piston and the spring described. The construction of the 80 antifriction device at the end of each piston rod is, likewise, a matter of selection, and in Figs. 9 and 10, I have illustrated one modification of the preferred construction, and in Figs. 11 and 12, I have shown another 85 modification thereof. These devices are so obvious and plainly illustrated in the said figures that a detailed description thereof is deemed superfluous.

Having thus fully described this invention, 90 I claim as new and desire to secure by Letters Patent of the United States—

1. A resilient wheel comprising a rim, a plurality of rigidly attached tubular spokes extending radially inwardly of said rim, a hub comprising an axial shank and a pair of spaced apart flanges, the free ends of said spokes being located between said flanges, means on said flanges contacting with the exterior wall of each of said spokes at a 100 plurality of points near the lower ends thereof, whereby driving force applied to said hub will be transmitted to said spokes at right angles to the axes thereof, plungers within said spokes having 105 their free ends contacting with said axial shank, and compressible means in said spokes acting upon said plungers.

2. A resilient wheel comprising a rim, a hub possessed of an axial shank and an 110 interior annular chamber surrounding said shank, there being a plurality of radial openings in the periphery of said hub, communicating with said interior chamber, a series of tubular spokes rigidly fixed to said 115 rim, entering said openings and slidably therein, means within said chamber adapted to contact with the exterior wall of each of said spokes near the lower ends thereof, whereby driving power applied to said hub 120 will be transmitted to said spokes at right angles to the axes thereof, plungers within said spokes having their free ends contacting with said axial shank, and compressible means within said spokes acting upon said 125 plungers.

3. A resilient wheel including a hub comprised of a hollow axial shank and a pair of cup shaped disks thereon with their marginal edges abutting, one of said disks being 130

formed integrally with said shank, means to maintain the other of said disks in position, there being radial openings in the periphery of said disks, a rim, a plurality of tubular spokes rigidly attached to said rim, the free ends of said spokes entering said openings and being slidable therein, means between said disks contacting with the exterior wall of each of said spokes near the lower ends thereof, plungers in said spokes having their free ends contacting with said axial shank, and compressible means within said spokes acting upon said plungers.

4. In a resilient wheel, a hollow hub, said hub including side plates having inwardly extending marginal flanges, one of said side plates having a centrally located boss on which the other of said side plates is centered in spaced relation, means for remov-

ably connecting said side plates including 20 bolts, a series of spokes radiating from said hollow hub, a rim to which the outer ends of said spokes are removably secured, compression means in said spokes constructed to resist inward movements of said spokes 25 in said hub, and a series of guiding rollers in said hub near the ends of said spokes said rollers being journaled upon said bolts between each two adjacent spoke ends.

In testimony that I claim the foregoing 30 as my invention, I have hereunto set my hand in the presence of two subscribing witnesses.

JOSEPH RENÉ AYOTTE.
